UNITED STATES PATENT OFFICE.

CHARLES A. MAHLA, OF NEW YORK, N. Y.

BATTERY-BOX.

1,077,539.

Specification of Letters Patent.

Patented Nov. 4, 1913.

Application filed March 6, 1913. Serial No. 752,525.

To all whom it may concern:

Be it known that I, CHARLES A. MAHLA, a citizen of the United States, residing at New York, in the county of New York and 5 State of New York, have invented certain new and useful Improvements in Battery-Boxes; and I do hereby declare the following to be a full, clear, and exact description of the invention, such as will enable others 10 skilled in the art to which it appertains to make and use the same.

This invention comprehends improvements in battery boxes and relates more particularly to dry battery boxes of the type 15 shown in my United States Patent No. 843,904.

The primary object of the invention resides in the provision of a battery box which shall be free from all wired connections, 20 which may be used in connection with any of the commercial types of dry batteries for ringing bells, driving fans, etc., and which is provided upon the under side of its cover with a plurality of spring contacts.

25 The invention also aims to generally improve dry battery boxes to render them more simple, more useful, and more commercially desirable.

With these and other objects in view, as 30 will become more apparent as the description proceeds, the invention consists in certain novel features of construction, combination, and arrangement of parts, as will be hereinafter described and claimed.

35 For a complete understanding of my invention, reference is to be had to the following description and accompanying drawings, in which,

Figure 1 is a longitudinal sectional view 40 through a battery box constructed in accordance with my invention, parts thereof being shown in elevation, Fig. 2 is a top plan view with the cover open, and, Fig. 3 is a detail sectional view of one of the 45 connections to be described later.

While I have shown my invention embodied in an alarm similar to the one disclosed in my former patent, it is to be understood that the battery box is capable 50 of a much more general use and I do not wish to be limited to this specific application.

Referring in detail to the drawings by numerals, 5 designates a casing which is preferably in the form of a wooden box of rec-

tangular cross section and provided with a cover 6 hinged, as indicated at 7.

8 designates a dry battery of any common type having one pole indicated by the binding post 9 and another pole 10.

An electro-magnetic bell 11 is secured to the exterior of the box by means of the screws 12 and 13, having nuts 14 threaded upon the inner ends thereof. The screw 13 extends through the base plate of the 65 bell and through the wall of the box and is insulated from the former by the sleeve 14'. A wire 15 is secured to the screw 13 by means of a nut 16 and represents one end of a coil which forms a part of the electro- 70 magnets of the bell. This wire is insulated from the base plate of the bell by a rubber coating 17.

A metallic standard 18 is secured to the top of the box by means of the metal screws 75 19 and has pivotally connected between its arms a metallic lever 20, which is adapted to be forced against the pressure of the spring 21 into engagement with a stud 22 which extends inwardly through the cover. 80 A pin 23 extends inwardly through one of the side walls of the cover and is threaded through the stud 22, as clearly shown in Fig. 1. The head of the pin 23 is spaced from the side walls of the cover 6, and a 85 metallic hook 24, which is pivotally secured to the metallic base of the bell by a suitable fastener 25, is adapted to lockingly engage said pin to hold the cover in its closed position.

A spring contact strip, generally designated 26, is secured to the inner side of the cover by means of suitable fasteners 27 and extends inwardly and to one side of the box, as indicated at 28, and is then bent upwardly, as indicated at 29, so that when the cover is closed the strip will engage the binding post 9 and nut 14. A contact plate 30 is connected to the screws 19 by the nuts 31 and is formed with the spring arm 32, 100 which, when the cover is closed engages the pole 10 of the battery.

33 designates an angular arm which is adapted to support the battery box by engaging over a door knob, and 34 designates 105 a loop which catches on the shank of the door knob when the latter is turned, whereby the lever 20 is thrown into engagement with the stud 22.

When the cover is secured in its closed po- 110

sition by the hook 24, a circuit from the battery through the bell is closed by bringing the lever 20 into contact with the stud 22. When this has been done, current may flow 5 from the binding post 9 through the contact strip 28 and nut 14 to the screw 13, then through the coils of the electro-magnets, the metallic base of the bell, the hook 24 and its connections, and back to the battery box by 10 way of the lever 20 and contact plate 30. When the device is not being used as a burglar alarm, the hook 33 and loop 34 may be dispensed with and any suitable means employed for connecting the standard 19 and 15 stud 22. In place of the bell 11, I may substitute any desired device or may connect any electrically operated object in circuit with the screw 13 and hook 24.

From the foregoing description taken in 20 connection with the accompanying drawings, it will be seen that I have designated a very simple dry battery box so constructed as to eliminate all wired connections, thus making it possible to easily and quickly 25 remove or insert a battery.

It is to be understood that while I have shown and described the preferred embodiment of my invention, I do not wish to be limited to this exact construction, combination, and arrangement of parts, but may make such changes as will fall within the spirit and scope of the invention.

Having thus described my invention, what I claim is:—

35 1. A battery box having a hinged cover, contact members carried by said cover and adapted to engage the poles of a battery within the box, a terminal member extending into the box and adapted to be engaged 40 by one of said contact members, means for locking the cover in its closed position, said means forming a second exterior terminal, and circuit closing means positioned upon the cover of the box.

2. A battery box having a hinged cover, 45 spring contact members carried by said cover and adapted to engage the poles of a battery within the box, a terminal member extending through the wall of the box to engage one of said contact members, means 50 for locking the cover in its closed position, said means forming an exterior terminal, and circuit closing means carried by the cover for engagement with said fastening means.

3. The combination with a battery box having a hinged cover, of a battery positioned within said box, spring contact members carried by the cover and adapted to engage the poles of said battery, a screw extending through the wall of the battery box, a fastener secured upon the inner end of said screw and adapted to engage one of said contact members, said screw forming an exterior terminal, a hook pivoted to the box 65 and forming the other exterior terminal, means carried by the cover for engagement by said hook whereby the cover is held in its closed position, and circuit closing means positioned upon the cover.

4. In combination, a battery box, a battery positioned therein, movable contact members carried in said box for engagement with the pole of the battery, a terminal member extending into the box and engaging 75 one of the contact members, means for locking the contact members in engagement with the poles of the battery, said means including a pivoted member, and circuit closing means positioned upon the exterior of the 80 box.

In testimony whereof I affix my signature in presence of two witnesses.

CHARLES A. MAHLA.
